VENDING MACHINE

Louis H. Morin, Bronx, N. Y., assignor to The
Coca-Cola Company, Wilmington, Del., a cor-
poration of Delaware

Application July 22, 1936, Serial No. 91,837

6 Claims. (Cl. 312—36)

This invention relates to machines for vending various kinds and classes of bottled goods, and particularly, beverages, especially from a cooled or chilled compartment or storage chamber in the machine; and the object of the invention is to provide improved means for supporting, feeding and delivering bottles to facilitate the removal thereof from the machine, and particularly where such feed and delivery is controlled by a coin mechanism; a further object being to provide a vending machine having an opening therein through which the bottles to be vended are adapted to pass, with automatically actuated means for normally closing said passage to prevent unauthorized admission to the storage chamber of the machine; a further object being to provide an endless bottle feeding conveyor, involving relatively long bottle supporting tubes linked together to form said conveyor, the axis of the links forming the mounting of the tubular bottle supports in connection with said links; a further object being to provide means for indicating to the operator when the machine is empty in order to eliminate and avoid the inconvenience of inserting a coin into the machine and the removal of the returned coin therefrom; a still further object being to provide means involving a crank for actuating the conveyor and for cushioning the crank action, especially when released by the operator to render the machine substantially noiseless in operation; and with these and other objects in view, the invention consists in a vending machine of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a side and sectional view of the upper end portion of the vending machine, indicating the method of its use.

Fig. 2 is a partial section on the line 2—2 of Fig. 1.

Fig. 3 is a partial section on the line 3—3 of Fig. 1.

Fig. 4 is a partial section on the line 4—4 of Fig. 1.

Fig. 5 is a view similar to Fig. 1, showing only a part of the construction with parts in a different position.

Fig. 6 is a sectional detail view of the upper end portion of a drive which I employ.

Fig. 7 is an enlarged detail view of a part of the conveyor, with parts of the construction broken away, and in section; and,

Fig. 8 is a sectional detail view of one corner portion of the machine, the section being substantially on the line 8—8 of Fig. 1.

The present invention relates primarily to the mechanical parts of the vending machine controlling and regulating the feed and discharge of the bottles or other merchandise to be vended. I have illustrated a coin control mechanism for controlling the operation of the machine, but this mechanism, per se, forms the subject matter of a companion application filed of equal date herewith, certain parts of this mechanism being illustrated to clearly show the cooperation between the manually actuated crank and the driven conveyor as well as other associated or inter-related parts, for example, the shock absorbing cylinder or dash-pot and the "Empty" indicating device. In referring to the dispensing of bottles as containers for various kinds and classes of beverages, it will be understood that the invention is also applicable to other kinds and classes of merchandise suitable for dispensing in a machine of the kind herein described and claimed.

To illustrate one use of my invention or method of carrying it into effect, I have indicated at 10 in the accompanying drawings, the upper end portion of a box or container which might also be referred to as a cabinet. This container is of double wall structure with suitable insulation 11 between the inner and outer walls to maintain the inner storage or cooling chamber 12 fully insulated to maintain the desired temperature in said chamber. In dispensing beverages, I employ a suitable fluid 13 in the chamber 12 which may be cooled by ice arranged in the rectangular space indicated at 12a, in Fig. 3 of the drawings, or this water may be chilled by suitable refrigerating means in the form of conventional electric and other refrigerating units. Should it be desirable to dispense heated drinks or beverages, the process may be reversed and suitable heating agents employed.

In the present construction, the apparatus is designed to dispense or vend elongated bottles or containers 14 for beverages or drinks of various kinds and classes. Supported on suitable brackets 15 arranged in the chamber 5 is a conveyor supporting frame 16 serving as a support and guide for a plurality of bottle supporting tubes 17 forming part of a conveyor. The tubes

17 are open at opposite sides as indicated at 18 and have a bottom crosshead 19 mounted upon the pivot and coupling pins 20 of pairs of links 21, 22 of an endless chain. The links 21, 22 are each 5 formed from flat strips of metal perforated at their ends to receive the coupling or pivot pins 20; and one end portion 23 of each link is set inwardly with respect to the other end portions 24 so that the set-in ends 23 of one pair of links 10 fit within the end portions 24 of an adjacent pair of links as clearly represented in Fig. 7 of the drawings. The central portions 20a of the pins 20 are enlarged, and arranged thereon are rollers 25 which provide anti-frictional engagement with 15 a drive sprocket 26 secured to the lower end of a vertical drive shaft or tube 27.

Arranged upon and detachable with respect to the upper open end of the container 10 is a casing 28 in connection with which the coin controlled mechanism 29 of the machine is supported. 20 At 30, I have shown an insulated cover which is detachable with respect to the top of the container or cabinet 10 to form a closure therefor which will be secured and sealed in place in any desired manner to maintain the proper temperature 25 in the chamber 12 as well as to prevent unauthorized admission to said chamber. The cover 30 in the construction shown includes an upwardly extending part 30a which cooperates with the casing 28 to form a closure. This extension permits removal of the cover regardless of the position of the parts supported in connection therewith. The cover 30 is provided adjacent the casing 28 with an opening reinforced by a ring frame 31 having an outwardly and upwardly flared 30 throat 32 which forms the discharge opening proper of the cover and through which the bottles 14 are adapted to pass.

Supported on the under side of the cover 30 are 40 two tracks or guide rails 33 in connection with which a sliding door or closure 34 is mounted. The guide rails 33 have a transverse stop bar 35 which cooperates with a downwardly projecting curved end 36 on the door 34 to limit the movement of said door in one direction. The rear end 45 of the door 34 is provided with a projecting arm 37 with which is coupled a spring 38 which serves to normally maintain the door in closed position.

Pivoted supported in the downwardly directed 50 curved portion 36 of the door as seen at 38 is a pawl or catch device 40, the pivoted end portion of which is provided with a rounded projecting tongue 41. The other end of said pawl is in the form of a long arm having a notch 42 at its end 55 adapted to engage the bar 35 to latch or retain the door in closed position, it being understood that the pawl 40 drops by gravity to bring the notch 42 into engagement with the bar 35, whereas in the operation of dispensing or moving a 60 bottle 14 upwardly through the discharge opening 32 in the operation of the machine, the upper end portion of the bottle first strikes the pawl tongue 41, disengaging the notched end 42 of the pawl from the bar 35. As the bottle continues to advance upwardly and move from right to left, the door is moved from right to left from the position shown in Fig. 5 to the position shown in Fig. 1, in which latter position, the bottle, or the upper end thereof, has been projected above the top of the 65 cover 30 in the manner illustrated and may be readily grasped by the customer and drawn upwardly through the opening 32. The instant that the bottle is released from the door 34, the door automatically moves into its closed and 70 locked position by the spring 38.

The conveyor has its links and bottle receiving supporting tubes arranged in inner and outer tracks, and in the operation of the machine, the inner track is moved from right to left as seen in Fig. 3 of the drawings. When a bottle assumes a position in the tubular support represented at x in Fig. 3, preparatory to being discharged when the said supporting tubes reach the position indicated at x2 in Fig. 3, which relative positions are also indicated by the reference characters x 10 and x2 in Fig. 1 of the drawings, the bottle, in traveling from the position of the receptacle at x to the position x2, travels or slides over upwardly inclined cams or slideways 43 secured to the frame 16 and arranged at the opposite cut-out sides 18 15 of the tubular supports 17 so that each bottle 14 is elevated from the position shown at x to the position shown at x2 in Fig. 1. In vending different kinds and classes of merchandise, the contour and arrangement of the lifting or ejector cams 20 will be modified to suit the particular kind and class of merchandise employed. This is also true of the form and construction of the article supports 17 employed.

Pivotedly supported in connection with the 25 frame 16 as indicated at 44, is a lever 45, one end portion of which has an upwardly directed extension 46 adapted to normally lie in the path of movement of the lower ends of the bottles or other articles when moved into the position represented 30 at x so that in the normal operation and when an article or bottle 14 is in a holder 17 when in the position designated at x, the extending end 46 is depressed; and, on the other hand, if this holder 17 is empty and an article or bottle 14 is not in 35 position to be dispensed or vended, the end 46 will assume a raised position by the other weighted end portion 47 of the lever 45.

Coupled with the end portion 47 is a vertical rod 48 which extends upwardly through the shaft 40 27 and includes at the upper end thereof an offset arm 49 having a cam portion 50 which is adapted to engage a spring pressed pin 51 so as to throw an "Empty" indicating sign 52 in position to register with a window or opening 53 in the wall 45 of the casing of the coin mechanism 29. The sign 52 is in the form of a lever pivoted at 54 and the end 55 of said lever is mounted on the pin 51, said spring pressed pin 51 serving to normally support the "Empty" sign 52 in inoperative or 50 invisible position, which position is assumed by the sign when the end 46 is maintained in depressed position by a bottle. The upper surface of the end 46 is sufficiently long to at all times engage one of the bottles when supported in the 55 respective holders.

The lower end of the shaft 27 has a universal mounting in the frame 16 as indicated at 56. The upper end of the shaft has a square shank 27a fitting in a square socket 57 of a drive disk 58 60 which is intermittently driven by a segmental gear 59 through a coin introduced into the machine and acting as a key or coupling between the beveled gear segment 59 and said disk, as more fully described and claimed in a companion application of this coin mechanism.

In the accompanying drawings, I have diagrammatically illustrated at 60 a part of the coin slot for guiding a coin 61 into position between the parts 58 and 59 as indicated in Fig. 1. Further specific reference to this mechanism will be omitted as it forms no direct part of the present application.

Mounted in a suitable bushing 62 in the casing of the coin mechanism 29 is a crank shaft 63 hav- 75

ing an offset crank handle 64 for actuating the same. Secured to this shaft is a driving block or sleeve 65 having an offset stop 66 for limiting the movement of the crank shaft 63 in one direction.

5 Coupled with this sleeve 65 through a shearing pin 67 is a beveled gear segment 68 having an offset stop arm 69 for limiting the movement of the crank shaft 63 in the opposite direction. This structure is shown in Figs. 1 and 6 of the drawings. The segment 68 is adapted to mesh with the beveled gear segment 59 to transmit the rotary movement of the crank shaft 63 to the gear 59 to rotate the shaft 27 in the manner heretofore described. The shearing pin coupling 67 employed provides a breaking pin between the crank and operative mechanisms of the machine to prevent stresses or strains thereon should parts of the machine become inoperative by accident or otherwise.

20 I also employ a shock absorbing unit for cushioning the movement of the crank in both directions to render the operation of the machine substantially noiseless as well as to relieve the crank from excessive stress. This mechanism is mounted in a suitable bracket or frame 70 supported in the casing of the coin mechanism in any desired manner, said bracket having a cylinder portion 71, note Fig. 2 of the drawings, in which is arranged a piston 72, the connecting or plunger rod 73 of which is pivoted to a projecting arm on a gear segment 74 supported in the part 75 of the bracket. The gear segment 74 meshes with a pinion 76 keyed to the crank shaft 63 as seen in Fig. 2 of the drawings. In other words, in the rotation of the crank shaft 63, or in drawing the crank arm 64 forwardly into the position indicated in dotted lines in Fig. 2, in the operation of discharging a bottle 14 from the container or moving the same into the position shown in Fig. 1 of the drawings at x2, the piston 72 is moved to the right and compresses a spring 77 in this operation, which acts to cushion the forward movement of the crank 64. When said crank is released by hand, the spring 77 urges the piston to the left, and the air in the cylinder 71 in front of the piston will be discharged slowly through a small port 78 in the manner of a dash-pot action, thereby cushioning said return movement of the crank 64. In this connection, it is understood that air is admitted into the cylinder 71 in the first named stroke of the piston through a check valve 79 in the head end of the cylinder.

In the aforesaid operation of the crank, the coupling collar 65 including the gear segments 68 are moved into the position shown in Fig. 6, in which operation and assuming that a coin 61 is in position between the parts 58 and 59, the shaft 27 will be caused to be rotated, which, in turn, rotates the sprocket 26 secured to said shaft to feed the conveyor to move one of the containers 17 from the position shown at x into the position shown at x2 and to move a bottle 14 from the position shown at x in Fig. 1 into a position similar to that represented at x2 in said figure. In this operation, the door 34 is automatically opened in the manner heretofore described and the bottle may then be removed from the container. This operation will continue as long as bottles remain in the respective and successive supports 17 on the conveyor. In the event that an empty support appears in the position x the sign 52 with the word "Empty" thereon will appear in the opening or sight glass 53. At the same time, the spring pressed pin 51 will be moved into position to transverse the coin slot

60 to reject or return a coin inadvertently placed into the coin mechanism by an operator, should the sign 52 be unnoticed at the time.

From time to time, new bottles or other articles 14 may be placed in the empty holders 17 as well as replacement made of cooling or heating agents or mediums when the latter are not automatic or continuous in operation. With the construction forming the subject matter of this invention, any particular type or kind of coin controlled mechanism may be employed. In fact, in some uses of the invention, where the coin mechanism is not essential, the apparatus may be used simply as a storage means, and means for conveniently removing bottles or other articles from the container whenever desired. In other words, the device may be used for selling or serving beverages and the like, while keeping the stored or un-served beverages in a cool or otherwise preserved state.

20 My improved conveyor provides means for moving the bottles or other articles through the container to bring the same into position to be discharged by a structure which is not only simple but economical and practical in use, and 25 one which is not likely to bind or jam. The anti-friction rollers 25 provide free action upon the sprocket 26 and the tubular supports 17 of the conveyors will provide the desired flexibility and yet operate to maintain the bottles in spaced relation one with respect to the other in traveling around the conveyor track. After a bottle has been removed from a support 17 when arranged directly beneath the opening 32, said support 17 remains in this position in an empty state until 30 the conveyor is again rotated by the crank 63, which rotation is controlled by the coin mechanism in the construction shown.

It will be noted upon a consideration of Fig. 1 of the drawings that the tubular supports 17 are 40 of sufficient height to support the bottle when in its projected position, and the bottle is projected sufficiently through the opening to enable the purchaser to freely grasp the same to withdraw the bottle from the machine. It will also 45 be noted upon a consideration of Fig. 3 of the drawings that the drive sprocket 26 on the shaft 27 is located at one corner of the conveyor so as to insure positive engagement with at least one of the bearing sleeves 25 on the pin 20 of the 50 conveyor chain at all times.

Having fully described my invention, what I claim as new and desire to secure by Letters Patent, is:

1. A vending machine having a storage chamber, an endless conveyor mounted in said chamber for supporting articles to be vended and for moving the same into position to be removed from the storage chamber through an opening in said machine, operating means for said conveyor, 55 means operable to automatically move one of the articles into a projected position with respect to the conveyor and the opening in said machine to facilitate the removal of the article therefrom, tube means on said conveyor for supporting the 60 article in its projected position, a door normally closing the opening in said machine, means engaged by the article in its movement into projected position for moving said door into open position, and a catch normally locking the door 65 in closed position, said catch being released by the article in the operation of engaging and moving said door.

2. A vending machine having a storage chamber, an endless conveyor mounted in said chamber, 70

- ber for supporting articles to be vended and for moving the same into position to be removed from the storage chamber through an opening in said machine, operating means for said conveyor,
- 5 means operable to automatically move one of the articles into a projected position with respect to the conveyor and the opening in said machine to facilitate the removal of the article therefrom, tube means on said conveyor for supporting the
- 10 article in its projected position, a door normally closing the opening in said machine, means engaged by the article in its movement into projected position for moving said door into open position, a catch normally locking the door in
- 15 closed position, said catch being released by the article in the operation of engaging and moving said door, and spring means automatically moving the door into closed position when the article is removed from the machine.
- 20 3. A vending machine having a storage chamber, an endless conveyor mounted in said chamber for supporting articles to be vended and for moving the same into position to be removed from the storage chamber through an opening in said
- 25 machine, operating means for said conveyor, means operable to automatically move one of the articles into a projected position with respect to the conveyor and the opening in said machine to facilitate the removal of the article therefrom,
- 30 tube means on said conveyor for supporting the article in its projected position, a door normally closing the opening in said machine, means engaged by the article in its movement into projected position for moving said door into open
- 35 position, a catch normally locking the door in closed position, said catch being released by the article in the operation of engaging and moving said door, spring means for automatically moving the door into closed position when the article is removed from the machine, the means for actuating said conveyor including a crank shaft having a crank arm, and means for cushioning the movement of said arm in two directions.
- 40 4. A vending machine of the class described having means for supporting and storing articles to be discharged through an opening formed in the machine and accessible through one wall structure of the machine, means involving an automatic spring closing a latching door for
- 45 closing the discharge opening in said machine, means whereby an article engaging said door, in the operation of moving the same into position to be discharged through said opening, will cause said door to be unlatched and moved into open position, and means in the machine adjacent the discharge opening therein for automatically feeding the article into position to project outwardly through said opening to facilitate the removal of the article from the machine.
5. In a vending machine, a storage compartment, means involving an endless conveyor for supporting articles in said compartment and for moving the same into position to be discharged from said machine, said conveyor comprising a
- 10 plurality of elongated tubes in which the articles are independently supported, pairs of links pivotally coupling adjacent tubular supports, adjacent ends of successive pairs of links being arranged on common pivots to form an endless chain structure for said conveyor, said tubular supports being mounted upon the pivots of adjacent pairs of links, and the lower ends of said tubular supports being cut out at opposite sides adjacent the end portions thereof attached to
- 15 the pivots of said links.
6. In a vending machine, a storage compartment, an endless conveyor for supporting articles in said compartment and for moving the same into position to be discharged from said machine,
- 20 said conveyor comprising a plurality of elongated tubes in which the articles are independently supported, pairs of links pivotally coupling adjacent tubular supports, adjacent ends of successive pairs of links being arranged on common pivots
- 25 to form an endless chain structure for said conveyor, said tubular supports being mounted upon the pivots of adjacent pairs of links, the lower ends of said tubular supports being cut out at opposite sides adjacent the end portions thereof
- 30 attached to the pivots of said links, and a cam surface disposed in the path of movement of the containers of said conveyor and registering with the cut-out side thereof to engage the articles arranged in said supports to move such
- 35 articles longitudinally of the supports when moved relatively to said cam surface.

LOUIS H. MORIN.
